(57) **CLAIM**

The ornamental design for an endboard for a patient bed, as shown and described.

DESCRIPTION

FIG. 1 is a top front perspective view of an endboard for a patient bed showing our new design;

FIG. 2 is a top rear perspective view of the endboard of FIG. 1;

FIG. 3 is a bottom front perspective view of the endboard of FIG. 1;

FIG. 4 is a bottom rear perspective view of the endboard of FIG. 1;

FIG. 5 is a front elevation view of the endboard of FIG. 1;

FIG. 6 is a rear elevation view of the endboard of FIG. 1;

FIG. 7 is a first side elevation view of the endboard of FIG. 1;

FIG. 8 is a second side elevation view of the endboard of FIG. 1;

FIG. 9 is a top plan view of the endboard of FIG. 1; and,

FIG. 10 is a bottom plan view of the endboard of FIG. 1.

1 Claim, 6 Drawing Sheets
